UNITED STATES PATENT OFFICE

CHESTER L. MARSH, OF SENECA FALLS, NEW YORK.

IMPROVEMENT IN SNOW-SHOVELS.

Specification forming part of Letters Patent No. **148,077**, dated March 3, 1874; application filed December 29, 1873.

To all whom it may concern:

Be it known that I, CHESTER L. MARSH, of Seneca Falls, Seneca county, New York, have invented an Improved Method of Attaching Iron Points to the Blade of Snow-Shovels, &c., of which the following is a specification:

The object of my invention is to furnish a cheap and easily-adjusted iron point or tip to the blade of snow-shovels, grain-shovels, &c., for the purpose of preserving the shovel, and making a snow-shovel, for instance, better adapted to the purpose of cutting ice, snow, &c., of which—

Figure 1, in the accompanying drawing, is a side view, showing the barbed prongs B, which are driven into the end of a shovel-blade, H, as far as the shoulder A, as shown in Fig. 4, which is an end view, and which forms a fastening of the point to the blade, as shown in Fig. 2, which is a side view of the

blade with the point attached. Fig. 3 is a sectional end view, showing the position of the barbed prongs B in the blade, and the position of the point when attached, which is effected by simply driving the barbed prongs B, as shown in Fig. 1, into the end of a shovel-blade, as shown in Figs. 2 and 3, and the attachment is complete without the use of rivets or other means of attachment, making a cheap and efficient point or tip for snow-shovels, &c.

Now, therefore, what I claim as my invention is—

The metal tip A, provided with the barbed or notched prongs B for securing it to the wooden shovel-blade H, substantially as shown and described.

CHESTER L. MARSH.
